UNITED STATES PATENT OFFICE.

GEORGE H. GILMAN, OF BELMONT, MASSACHUSETTS, ASSIGNOR TO SULLIVAN MACHINERY COMPANY, A CORPORATION OF MASSACHUSETTS.

PRESSURE-FLUID MOTOR.

Application filed March 28, 1916, Serial No. 87,349. Renewed March 11, 1924.

To all whom it may concern:

Be it known that I, GEORGE H. GILMAN, a citizen of the United States, residing at Belmont, in the county of Middlesex and State of Massachusetts, have invented certain new and useful Improvements in Pressure-Fluid Motors, of which the following is a full, clear, and exact specification.

My invention relates to pressure fluid motors, and finds one of its most obvious adaptations in percussive drills and particularly those of the ground hog type, although it is not limited to use in that connection.

It has among its objects to provide an improved motor of small cross section wherein the necessity of providing valves located at the side of the same is avoided. A further object of my invention is to provide an improved drill of the valveless type having improved means for controlling the pressure fluid by the movement of the piston, and more particularly, improved means for supplying and exhausting the motive fluid. These and other objects of my invention will hereinafter appear.

In the accompanying drawings, I have, for purposes of illustration, shown one embodiment which my invention may assume in practice.

In these drawings,—

Figure 1 is an elevation of a drill of the ground hog type mentioned above, including its mounting, connections, etc.

Figure 2 is a partial longitudinal sectional view showing the drill cylinder with the piston in its extreme rearward position, the section being taken on line 2—2 of Figure 4.

Figure 3 is a view similar to Figure 2, showing the piston in its extreme forward position.

Figure 4 is a transverse sectional view taken on line 4—4 of Figure 2.

Figure 5 is a similar view taken on line 5—5 of Figure 2.

Figure 6 is a similar view taken on line 6—6 of Figure 2.

In the construction illustrated, I have shown a ground hog drill adapted to vertical drilling, it of course being understood that the same is adapted to use in drilling in any desired direction. This drill includes a cylinder 1 having a rotating mechanism 2 of any desired form connected to

the upper end of the same, the drill being 55 so-supported by a bracket 3 connected to the casing of the rotating mechanism and to a tripod 4, that the tool 5, the shank 6 of which extends into a chuck 7, may bore a vertical hole big enough to receive the cylinder 1, as the latter and the tool are fed by gravity, a supply pipe 8 being connected to the cylinder and also to a suitable source of pressure fluid supply through a hose 9.

The cylinder 1, as shown, is connected at 60 its tool-carrying end, hereinafter called its front end, through a coarse threaded connection 10 with the chuck 7, and similarly connected at its opposite, or rear, end at 11 to a sleeve-like member 12 threaded into the cylinder, and in turn threaded at its rear end at 13 to the front end of a supply pipe which may, and preferably does, form a part of the supply pipe 8. In the piston chamber 15 of this cylinder 1, moves a piston 16 preferably provided with a reduced hammer extension 17 on its front end adapted to move through an opening 18 in the front head of the cylinder 1 and strike the rear end of the tool shank 6. This piston 65 receives its supply of pressure fluid from the pipe 8, the latter delivering into the sleeve-like member 12 and that member delivering into a tube 19 preferably extending, 70 as shown, substantially half-way through the member 12 and within a sleeve-like portion 20, the latter preferably being formed on the movable rear cylinder head 21. As shown, this tube 19 not only extends through this head 21, but also through a second oppositely disposed sleeve 22 of slightly greater diameter preferably formed on the 75 opposite side of the head from the sleeve 20 and extending into a bore 23 formed in the piston 16 when the latter is in its rearward position shown in Figure 2. It will 80 also be noted that the tube 19 projects beyond this sleeve into the bore 23 and is provided with an enlarged end 24 preferably 85 on the same external diameter as the sleeve 22, and having a sliding fit with the piston and an annular flange 25 adapted to 90 form a seat for the front end of the sleeve 22 so that the latter may lie flush with the outer periphery of the portion 24 and the piston may reciprocate over both the sleeve 22 and the enlarged end 24 of the tube. The 95 air supplied to the tube 19 of course passes

through the same and to the piston bore, preferably passing out of the latter through lateral and preferably parallel passages 26 forming a communication between an inner 5 enlarged chamber 27 at the front end of the bore 23 and a series of longitudinally disposed grooves 28 formed in the periphery of the piston, these grooves preferably communicating, as shown, with a reduced portion or circumferential groove 29 intermediate the ends of the piston and being disposed on opposite sides of that reduced portion.

When the piston is in its rearward position shown in Figure 2, air supplied to the 15 piston bore 23 is conducted through these grooves 28 to an annular chamber or groove 30 formed in the inner periphery of the cylinder 1 and leading to the rear pressure surface 31 of the piston, so that the air may 20 act on that surface to project the piston forward to the position shown in Figure 2 and drive its hammer portion 17 into engagement with the end of the steel 6. As the piston thus moves forward to strike its 25 blow upon the steel, it uncovers oppositely disposed ports 32 in the front end of the sleeve 22 which communicate with a passage 33 disposed between that sleeve and the tube 19 and arising from the difference in 30 diameter of the tube and sleeve, mentioned above. Thus the air which has acted upon the rear pressure surface 31 of the piston is enabled to exhaust through these ports 32 and the passage 33 into an annular chamber 34 formed in the rear cylinder head 21, which in turn communicates through a series 35 of rearwardly extending passages 35 with a series of longitudinally disposed grooves 36 formed in the front threaded portion of 40 the sleeve member 12 and communicating with the atmosphere.

As the piston moves forward to strike the tool shank 6, its reduced end 17 of course closes the opening 18 in the front head of 45 the cylinder. It will also be noted that the grooves 28 are then placed in communication with an annular chamber or groove 37 in the front end of the cylinder. Thus, obviously, since the piston is constantly connected to the pipe 19, air from the pipe 8 will, in that position of the piston, be delivered to the front end of the cylinder so that it may act on the front pressure surface 38 of the piston and return the latter 50 from the position shown in Figure 3 to the initial position thereof shown in Figure 2. Obviously, as this occurs, the air which has acted expansively to return the piston will also be free to exhaust through the opening 55 18 in the front of the cylinder, suitable laterally disposed exhaust passages 39 also preferably being provided therefor, so that the air may find its way into the drill hole and through suitable cooperating longitudinally disposed grooves 40, provided in the 60 65

outer periphery of the cylinder, pass outward to the atmosphere.

From the above description it is believed to be apparent that air from the tube 19 will be again supplied through the grooves 28 to the annular groove 30 shortly after the piston starts on its rearward stroke. Thus, it will be noted that this air is enabled to act upon the rear pressure surface 31 of the piston and cushion the return stroke thereof, thereby reducing the danger of breakage of the rear head 21. It will also be noted that to supplement this cushioning effect, I have, as herein shown, provided a spring 41 coiled about the sleeve 20 on the head 21, and disposed in a chamber 42 formed in the front end of the sleeve 12, this spring acting between the sleeve 12 and the head 21 to absorb any blows struck the latter and to force the same to its normal position wherein an annular flange 43 thereon engages one or more annular washers 44 disposed between the same and a corresponding flange 45 formed on the cylinder. It will be obvious that by changing the thickness of this washer or substituting a plurality therefor, the position of the head 21 with respect to the cylinder may be adjusted as desired in order to vary the point in the piston stroke at which exhaust takes place and to vary the size of the piston chamber.

In the operation of the device shown herein for purposes of illustration, the drill steel normally rests against the work and is rotated by the rotating mechanism 2. Briefly reviewing the operation of the means for controlling the air, above described, it will be noted that when the air is admitted through the tube 19, it passes through the grooves 28 and acts upon the rear pressure surface 21 of the piston to drive the same forward to strike the steel shank 6, and is thereafter exhausted through the ports 32, the passages 33, etc. and grooves 36, to the atmosphere. After the piston has thus been driven forward to actuate the tool, the air passing through the grooves 28 and the grooves 37 also acts to return the piston through its action on the front pressure surface 38 thereof, this air thereafter exhausting through the opening 18, passages 39, and grooves 40. As brought out above, air is also admitted to the groove 30 during the latter part of the return of the piston, in such a manner as to cushion the latter on its return stroke and cooperate with the spring 41 in order to prevent breakage of the head 21.

In my improved construction, it will be noted that the pressure fluid which drives the piston forward is supplied and exhausted from the cylinder through axially extending passages disposed in the rear end of the cylinder, so that the device may be 120 125 130

made of exceedingly small cross section and without it being necessary to provide any ports or openings in the periphery of the cylinder or any lateral connections, thereby adapting it to use in various relations and making it especially valuable in connection with a drill of the ground hog type wherein it is desirable to reduce the cross section of the hole as much as possible and wherein a side exhaust is unsatisfactory for obvious reasons. Attention is also directed to the improved results obtainable as a result of the provision of my improved means for cushioning the piston, and to the simplified construction presented whereby the cost of production of the device is minimized. These and other advantages of my improved construction will, however, be clearly apparent to those skilled in the art.

While I have in this application specifically described one embodiment which my invention may assume in practice, it is to be understood that this form of the same is used only for purposes of illustration, and that the invention is in no wise limited thereto, but may be modified in various ways and adapted to other devices without departing from its spirit, it being my intention to include all such modifications within the scope of the appended claims.

What I claim as new and desire to secure by Letters Patent is:

1. A fluid motor comprising a cylinder, a piston reciprocable therein, and operating means therefor including coaxially disposed supply and exhaust passage forming means within said cylinder for the fluid acting therein and between which and said piston relative movement occurs, said exhaust passage means discharging directly to the atmosphere.

2. A fluid motor comprising a relatively stationary cylinder, a piston reciprocable therein, and operating means therefor including coaxially disposed supply and exhaust passages within said cylinder and between which and said piston relative movement occurs for the fluid acting in the rear end of said cylinder, said exhaust passage discharging directly to the atmosphere.

3. A fluid motor comprising a cylinder, a piston reciprocable therein and normally movable relative to said cylinder, and operating means therefor including coaxially disposed supply and exhaust passages within said cylinder and between which and said piston relative movement occurs for the fluid acting in the rear end of said cylinder, said exhaust passage discharging directly to the atmosphere.

4. A fluid motor comprising a cylinder, a piston reciprocable therein, and operating means therefor including coaxially disposed supply and exhaust passages within said cylinder and between which and said piston

relative movement occurs for the fluid acting in the rear end of said cylinder, said exhaust passage discharging directly to the atmosphere.

5. A fluid motor comprising a cylinder, a piston reciprocable therein, and operating means therefor including coaxially disposed supply and exhaust passages within said cylinder and adapted to have sliding telescopic engagement with said piston for the fluid acting in the rear end thereof, said exhaust passage discharging directly to the atmosphere.

6. A fluid motor comprising a cylinder, a piston reciprocable therein, and operating means therefor including coaxially disposed supply and exhaust passages within said cylinder and between which and said piston relative movement occurs for the fluid acting in the rear end of said cylinder, said exhaust passage discharging directly to the atmosphere from only one end thereof.

7. A fluid motor comprising a cylinder, a piston reciprocable therein, and operating means therefor including concentrically disposed supply and exhaust passage means within said cylinder and between which and said piston relative movement occurs for the fluid acting in the rear end of said cylinder.

8. A fluid motor comprising a cylinder, a piston reciprocable therein, and operating means therefor including concentrically disposed axially extending supply and exhaust passage means within said cylinder and between which and said piston relative movement occurs for the fluid acting in the rear of said cylinder.

9. A fluid motor comprising a cylinder and a piston reciprocable therein, said motor having supply and exhaust passage means within said cylinder and between which and said piston relative movement occurs for the fluid acting in one end of said cylinder, one of said passages being located within the other, and said exhaust passage discharging at the aforesaid end of said cylinder.

10. A fluid motor comprising a cylinder and a piston reciprocable therein, said motor having supply and exhaust passage means within said cylinder and between which and said piston relative movement occurs for the fluid acting in one end of said cylinder, one of said passages being located within the other, and said exhaust passage discharging directly to the atmosphere.

11. A fluid motor comprising a cylinder, an axially bored piston therein, a fluid supply tube extending into the bore of said piston and having sliding telescopic relation with the latter, cooperating means for distributing fluid for reciprocating said piston, and concentrically disposed axially extending means encircling said tube for conduct-

- ing away the exhaust from the rear end of said piston, said means discharging directly to the atmosphere.
12. A percussive tool comprising a cylinder, an axially bored piston therein, a fluid supply tube extending into the bore in said piston, cooperating means for distributing fluid for reciprocating said piston, and a sleeve disposed between said tube and cylinder provided with a longitudinally disposed exhaust passage and having an exhaust port therein controlled by said piston.
13. A percussive tool comprising a cylinder, a rear head therein, an axially bored piston movable in said cylinder, a supply tube extending into said piston through said rear head and relative to which said piston is movable, cooperating means for distributing fluid for reciprocating said piston, and a sleeve of greater diameter than said tube enclosing the latter and communicating with the atmosphere and the rear end of said cylinder.
14. A percussive tool comprising a cylinder, a rear head therein, an axially bored piston movable in said cylinder, a supply tube extending into said piston through said rear head, cooperating means for distributing fluid for reciprocating said piston, and a sleeve of greater diameter than said tube enclosing the latter and having exhaust ports therein controlled by said piston.
15. A percussive tool comprising a cylinder, an axially bored piston reciprocable therein, coaxially disposed supply and exhaust tubes extending into the rear end of said cylinder and the bore in said piston relative to which the latter is reciprocable, cooperating means for distributing fluid for reciprocating said piston, and supplemental means for discharging the exhaust from the front end of said cylinder.
16. A percussive tool comprising a cylinder, an axially bored piston movable therein, a supply tube extending into said cylinder having a body portion and an enlarged end extending into the bore in said piston, cooperating means for distributing fluid for reciprocating said piston, and an exhaust sleeve enclosing the body portion of said tube and having the flow therethrough controlled by said piston.
17. A percussive tool comprising a cylinder, a rear head therein, an axially bored piston movable in said cylinder, a supply tube extending through said head into said piston, means controlled by said piston, for distributing fluid for reciprocating the same, a sleeve enclosing the rear end of said tube, and means disposed between said sleeve and head for cushioning a return stroke of said piston.
18. A percussive tool comprising a cylinder, an axially bored piston in said cylinder, a supply tube extending into said piston bore, means for distributing fluid for reciprocating said piston and conducting pressure fluid to one end thereof to cushion a return stroke thereof, and supplementary resilient cushioning means cooperating therewith.
19. In a percussive fluid motor, a cylinder, fixed and slidale heads therefor, an axially bored piston movable between said heads, an exhaust member extending from said slidale head into the bore in said piston, means for reciprocating said piston, and means for limiting the movement of said slidale head longitudinally of said cylinder.
20. In a percussive fluid motor, a cylinder, fixed and slidale heads therein, an axially bored piston movable between said heads, an exhaust member extending from said slidale head into the bore in said piston, means for reciprocating said piston, means for adjusting said slidale head longitudinally of said cylinder, and resilient means normally resisting movement of said head in one direction.
21. A fluid motor comprising a cylinder, a rear head therein, an axially bored piston in said cylinder having front and rear pressure surfaces, concentrically disposed supply and exhaust tubes extending through said head into the bore of said piston, means for alternately conducting pressure fluid to said pressure surfaces, and cooperating resilient means for cushioning a return stroke of said piston.
22. A percussive tool comprising a cylinder having a slidale rear head, an axially bored piston in said cylinder, a supply tube extending through said head and into the bore in said piston, means for distributing fluid for reciprocating said piston, a sleeve enclosing the rear end of said tube and extending into said cylinder to a point adjacent said head, and a coiled spring disposed between said sleeve and head.
23. A percussive tool comprising a cylinder, a rear head having ports therein, an axially bored piston in said cylinder, a supply tube extending through said head and into the bore in said piston, means for distributing fluid for reciprocating said piston, and a larger exhaust tube enclosing said tube and communicating with the ports in said head, the flow through said exhaust tube being controlled by the movement of said piston.
24. A valveless tool comprising a cylinder, an axially bored piston movable therein, a supply tube extending into the bore in said piston, means controlled by said piston for supplying pressure fluid alternately to the opposite ends of the same, and axially disposed means for exhausting the pressure fluid from the opposite ends of the cylinder in opposite directions.

25. A fluid motor comprising a cylinder, an axially bored piston movable therein, a supply tube extending into the bore in said piston, means controlled by said piston for supplying pressure fluid alternately to the opposite ends thereof, and axially disposed means between which and said piston relative movement occurs and extending into the latter in one position thereof for conducting away the exhaust. 10
26. A fluid motor comprising a cylinder, an axially bored piston movable therein, a supply tube extending into the bore in said piston and between which and said piston relative movement occurs, means controlled by said piston for supplying pressure fluid alternately to the opposite ends thereof, and axially disposed means extending into said piston in one position thereof and disposed concentrically with said tube for conducting away the exhaust. 15
27. A fluid motor comprising a cylinder, an axially bored piston movable therein, a supply tube extending into said piston having an enlarged delivery end, means controlled by said piston and between which and said piston relative movement occurs for supplying fluid delivered by said tube to opposite ends of said piston, and an exhaust discharging member disposed concentrically with said tube and extending to a point adjacent the delivery end thereof. 20
28. A fluid motor comprising a cylinder, an axially bored piston movable therein, a supply tube extending into said piston having an enlarged delivery end, means controlled by said piston for supplying fluid delivered by said tube to opposite ends of said piston, and an exhaust discharging member disposed concentrically with said tube and extending to a point adjacent the delivery end thereof and having a port therein controlled by said piston. 25
29. A percussive tool comprising a cylinder, a rear head disposed within the rear end thereof having a rearwardly extending sleeve, an axially bored piston in said cylinder, a supply tube extending through said head into the bore in said piston, means controlled by said piston for distributing fluid for reciprocating the same in said cylinder, a sleeve communicating with the rear end of said tube and extending into said cylinder to a point adjacent said head, and a spring surrounding the sleeve on said head and disposed between the latter and said last mentioned sleeve. 30
30. A percussive tool comprising a cylinder, a rear head carried therein having oppositely disposed sleeves thereon, and axially bored piston movable in said cylinder, a supply tube extending through said head and sleeves and into the bore in said cylinder, means controlled by said piston for alternately conducting pressure fluid to the opposite ends thereof, cooperating means for conducting the exhaust from one end of said cylinder between one of the sleeves on said head and said supply tube, and communicating means for conducting the same axially between the other sleeve and said cylinder. 35
31. A percussive tool comprising a cylinder, a rear head carried therein having oppositely disposed sleeves thereon, an axially bored piston movable in said cylinder, a supply tube extending therough said head and sleeves and into the bore in said cylinder, means controlled by said piston for alternately conducting pressure fluid to the opposite ends thereof, cooperating means for conducting the exhaust from one end of said cylinder between one of the sleeves on said head and said supply tube, communicating means for conducting the same axially between the other sleeve and said cylinder, a sleeve-like supply member communicating with the rear end of said tube, and a spring acting between the same and said head and disposed between the other sleeve member and said cylinder. 40
32. In a percussive tool, a cylinder, an axially bored piston movable therein, a slideable rear head carried in said cylinder and having a port therein, a sleeve fixed to said head and extending into the bore in said piston in one position thereof and having a passage communicating with the port in said head, a supply tube extending into said piston and through said sleeve, cooperating means for reciprocating said piston in said cylinder relative to said tube and sleeve, a member attached to the rear end of said cylinder having a longitudinally disposed groove communicating with the port in said head, and resilient means disposed between said head and last mentioned member. 45
33. In a percussive tool, a cylinder, an axially bored piston movable therein, a slideable rear head carried in said cylinder and having a plurality of ports therein, a sleeve fixed to said head and extending into the bore in said piston in one position thereof and having passages communicating with the ports in said head, a supply tube extending into said piston and through said sleeve, cooperating means for reciprocating said piston in said cylinder relative to said tube and sleeve, a member attached to the rear end of said cylinder having a series of longitudinally disposed grooves communicating with the ports in said head, and resilient means disposed between said head and said last mentioned member and encircling the rear end of said tube. 50
34. A fluid motor comprising a cylinder, a piston reciprocable therein, said piston having an internal chamber, and a fluid supply conduit fixed with respect to said cylinder and communicating at its end with said chamber in all positions of said piston, said 55

motor having a fluid passage communicating with said cylinder in the rear of said piston and controlled by the relative position of said piston and conduit.

6. 35. A fluid motor comprising a cylinder, a piston reciprocable therein, said piston having an internal chamber, and operating means therefor including a fluid supply conduit fixed with respect to said cylinder and communicating at its end with said chamber in all positions of said piston and an exhaust passage within said cylinder for the fluid acting in the rear end thereof, said exhaust passage being controlled by the position of said piston and discharging independently thereof.

- 10 36. A valveless fluid motor comprising a stationary cylinder, a hollow piston reciprocable therein, said motor having fluid distribution means comprising a fluid supply tube between which and said piston relative movement occurs and carried by the cylinder and projecting longitudinally thereinto, said tube being constantly connected during operation of the motor with live fluid pressure, and supplying the same to the interior of said piston for distribution thereby to effect reciprocation thereof, and being provided at its exterior with means to conduct away the exhaust from one end of said cylinder.

15 37. A fluid motor comprising a cylinder, heads thereon, a piston reciprocable in said

cylinder, said piston having an internal chamber, and fluid distribution and exhaust means for said motor comprising fluid supply and exhaust passage forming tubes projecting into said cylinder from one head thereof, one of said tubes having its free extremity so positioned as to remain within said internal chamber during movement of the piston relatively to said tube, another of said passage forming tubes surrounding said first mentioned tube and ending at a point between the free extremity of said first tube and the cylinder head and operating when free of the piston as an exhaust conduit for one end of said cylinder.

10 38. A fluid motor comprising relatively movable cylinder and piston members, and operating means therefor including coaxially disposed supply and exhaust passage forming means for the motive fluid, said passage forming means projecting within said cylinder and between which and said piston relative movement occurs.

15 39. A fluid motor comprising relatively movable cylinder and piston members, and operating means therefor including coaxially disposed supply and exhaust passage forming means for the motive fluid, said passage forming means having telescopic sliding relation with said piston.

In testimony whereof I affix my signature.

GEORGE H. GILMAN.
